UNITED STATES PATENT OFFICE.

GEORGE E. NUEBLING, OF READING, PENNSYLVANIA.

PORTABLE HAND-PUNCH.

SPECIFICATION forming part of Letters Patent No. 340,727, dated April 27, 1886.

Application filed February 11, 1886. Serial No. 191,566. (No model.)

To all whom it may concern:

Be it known that I, GEORGE E. NUEBLING, a citizen of the United States, residing at the city of Reading, county of Berks, State of Pennsylvania, have invented a new and useful Improvement in Portable Hand-Punches, of which the following is a specification.

This improvement relates more particularly to the class of portable punches used in the construction of boiler-tanks, &c.

The object of the improvement is to furnish boiler-makers and metal-workers generally with a hand-punch not liable to get out of order, having the working parts concealed, and free from liability to dirt and damage, and all parts easily and cheaply replaced, with the excessive friction of the ordinary screw-punch eliminated by transferring the pressure to a bed of anti-friction rollers.

Referring to the drawings accompanying this specification and forming a part of the same, and in which similar letters of reference designate similar parts, Figure 1 represents the frame of the punch in side elevation with the front portion of the same in section, showing the arrangement of the working parts. Fig. 2 represents in plan the anti-friction-roller bed and rollers for receiving the thrust of the punch.

In exterior appearance my improved punch does not differ materially in form of frame, jaws, and head from the punches usually found in boiler-shops; but a closer examination reveals the fact that its construction is a decided advance in the hand-punch line.

The construction is as follows: The frame A is provided with the usual jaw, A', and a head, A'', a trifle larger in its diameter than the usual direct screw-threaded head, which is bored to receive the spindle C, and has a threaded counterbore, A³, at its upper end, a recessed seat, A⁴, in the lower jaw for the die, and a tapered bore, A⁵, beneath the same. The cap B has a threaded extension, B', to connect with the frame at A³, is bored at B² for the neck of the punching-screw, and counterbored at B³, to form a bed adapted to receive the anti-friction rollers F. The spindle C is fitted to the bore of the head A'', and is counterbored from its upper end to form a seat, C', to support the renewable nut D, and from its outer end to

form a seat, C², for the head H' of the punch. The renewable nut D is turned to fit the bore of the spindle C with a very slight play, its collar D' fitted to an accurate bearing upon 55 the end of the spindle, and its lower end, D², to a coincident bearing upon the seat C', the interior threaded to fit the punching-screw E, and the spindle C and nut D held in mutual connection with the screw E by a 60 removable pin, D³, as shown. To prevent the turning of the spindle and revolution of the punch, a guide-spline, A⁶, is formed in the bore of the head just beneath the cap B, of a length to admit of the full travel of the punch, and a 65 feather-key, or its equivalent, D⁴, is secured in the upper end of the spindle at C³, which, as the punch H is raised or lowered by the revolution of the screw E, travels in said 70 spline and restrains the spindle, nut, and punch from a circular movement. The punching or operating screw E, which is threaded to fit the nut D, is formed with a strong collar, E', with a neck, E², projected above the same, which is threaded at E⁴, for connection with 75 the threaded counterbore G' of its removable head G, being additionally secured therewith by a pin, G³. The collar E' is fitted to the bore of the cap B, and its upper face, E², is turned to form a bed for the anti-friction rollers F, 80 which are made of such diameter and length as just to fill out the space left between the collar and cap and the neck of the screw and bore of the cap, as shown.

As constructed a small space is left between 85 the nut and collar when the spindle is drawn up within the bore. This forms a reservoir, which will be filled with oil, and as the screw is operated will lubricate the moving parts. The punch H is secured in the usual manner 90 to the spindle by a sunk tap-screw, H².

The operation of the punch is as follows: The screw is operated to raise the nut and to retract the spindle and punch. The plate is then laid upon the die, and the movement of 95 the screw being reversed the nut, spindle, and punch advance without revolution, and the plate is punched, the thrust of the punch being resisted by the cap, and its force converted into a rolling friction by the interposed 100 anti-friction rollers F, as shown, thereby materially reducing the power required to oper-

ate the same. I prefer to form the screw with its collar and the cap, together with the anti-friction rollers, of steel or some equivalent metal.

5 Having shown the construction, use, and advantages of my improved hand-punch, I desire to claim as follows:

1. The combination, with the frame A and head A², of a portable hand-punch, of a non-revolute spindle, C, having a counterbore at its inner end forming a seat, C', for a removable nut, D, a counterbore at its outer end forming a seat, C², for the head of the punch, and a feather-key or its equivalent, C³, moving 15 in a spline, A⁶, adapted thereto, said nut D removably secured to the spindle C by a pin, D³, substantially as shown, described, and for the purpose set forth.

2. In combination with a non-revolute 20 spindle and nut of a hand-punch, its head and frame, as shown and described, a screw spindle, E, having a collar, E', fitted to revolve in the cap B, a beveled upper face or seat, E², neck E³, and removable head G, cap B, thread-

ed extension B', counterbore-seat B³, adapted 25 by bore B² to the neck of the screw, with a series of anti-friction rollers, F, surrounding the neck E³ and held between the cap-seat B³ and collar-seat E², substantially as and for the purpose specified.

3. In a portable hand-punch, the combination, essentially, of the following elements: a frame, A, having jaws A', head A², threaded counterbore A³, die-seat A⁴, tapered aperture A⁵, spline A⁶, with cap B, threaded to fit counterbore A³, adapted to the neck of the screw-spindle, and having a seat or bed for the anti-friction rollers F formed in the same, the top forming a seat for the operating-head G, a non-revolute spindle having a removable 40 nut, D, therein, and feather-key C³, reservoir J, punch H, and die I, all arranged, combined, and adapted to be operated in the manner and for the purpose set forth.

GEORGE E. NUEBLING.
